UNITED STATES PATENT OFFICE

EARL PHILLIP JONES, OF FORT LAUDERDALE, FLORIDA, ASSIGNOR TO GATE CITY SASH & DOOR COMPANY, OF FORT LAUDERDALE, FLORIDA, A CORPORATION OF FLORIDA

LOUVER CONSTRUCTION

Application filed June 19, 1930. Serial No. 462,172.

This invention relates to louvers or blinds or shutters for doors and windows and other places on houses and buildings.

Generally stated, the object of the invention is to provide a novel and improved construction whereby each slat or shutter of the louver construction has two parallel axes of motion, thereby to provide means for simultaneously moving all of the slats or shutters into either open or closed position, as may be desired.

It is also an object to provide certain details and features of construction and combinations tending to increase the general efficiency and the desirability of a louver construction of this particular character.

To the foregoing and other useful ends, the invention consists in matters hereinafter set forth and claimed and shown in the accompanying drawings, in which—

Fig. 1 is a front elevation of a set of louvers or blinds for a window, or other similar opening, embodying the principles of the invention.

Fig. 2 is a horizontal section on line 2—2 in Fig. 1 on a larger scale.

Fig. 3 is an enlarged vertical section on line 3—3 in Fig. 1 of the drawings.

Fig. 4 is a view similar to Fig. 3, showing a single set of louver shutters in closed position.

Fig. 5 is a side elevation of one of the movable connecting members to which the ends of the louver slats are connected.

Fig. 6 is a plane view of one of the louver slats, on a larger scale, with the middle portion thereof shown broken away for convenience of illustration.

Fig. 7 is an edge view of the shutter shown in Fig. 6 of the drawings.

Fig. 8 is a front elevation of a door provided with a set of louvers or shutters embodying the principles of the invention.

Fig. 9 is an enlarged vertical section on line 9—9 in Fig. 8 of the drawings.

Fig. 10 is an enlarged vertical section on line 10—10 in Fig. 8 of the drawings.

Fig. 11 is a horizontal section on line 11—11 in Fig. 10 of the drawings.

As thus illustrated, referring to Figs. 1

to 7 of the drawings, the invention comprises a rectangular frame 1, having a plurality of openings therein. The sides of said openings are preferably provided with stationary cleats 2 as shown. The cleats 3 are vertically movable in said frame, and in said openings. Louver slats or shutters 4 have their ends provided with pivots 5 mounted in the cleats 2, and said shutters have their ends provided with pivots 6 mounted to turn in the cleats 3 previously mentioned. Therefore, of course, when the cleats 3 are moved up and down the shutters or louver slats 4 are tilted about their fixed axes provided by the pivots 5 previously mentioned. When the cleats 3 are moved downwardly the slats are opened. Preferably, as shown in Fig. 3 of the drawings, the cleats 2 and 3 are similarly and relatively formed to engage each other along a zigzag line, whereby the shutters are each nearly in a vertical plane when the same are in closed position. To open the shutters, the cleats 3 are moved downward, by any suitable means. It will be understood, of course, that any suitable means, such as friction in the pivot bearings, or anywhere else, can be employed for holding the shutters in closed position, or in partially opened position. When the shutters are open, the cleats 3 bear against the inner side 7 of the frame as shown and are supported in this position by the frame, thus holding the shutters in horizontal planes, thereby providing the maximum space or opening between the shutters. When the slats or shutters are closed, the pivots are all uniformly spaced vertically, whereby the cleats 2 and 3 are duplicates in formation.

As shown in Fig. 6, the shutters may have metal ends 8 provided with said pivots, if such is desirable or necessary.

As shown in Figs. 8 to 11 inclusive, the construction is similar, but in this case the rectangular frame 9 takes the form of a door. In this case, the cleats 10 are stationary, like those previously described, while the cleats 11 are vertically movable like those previously described. The shutters 12 are rigid with the pivots 13 and 14, as previously described, and the mode of op-

eration of the louver or shutter thus provided is similar to that previously explained. In each form of the invention, a horizontal cleat 15 is preferably provided to form a stop for the lower blade or shutter of the louver construction, when the shutters are in fully closed position. In this way, the shutters fold in overlapping relation and shed water from the outside. Furthermore, 10 if desired, screens 16 may be provided in the frame, outside of the shutters, and in this way screens are provided outside of the louver shutters, which are controllable from the inside of the house or building.

15 Thus it will be seen that a simple and inexpensive form of louver or shutter construction is provided, as a part of a door or window or other closure, of such character that the louvers or shutters can be controlled 20 from the inside of the house or building, it being understood that the rectangular frame shown in Figs. 1 to 4 inclusive, or the rectangular frame shown in Fig. 8, may occupy a position in the door or window opening, 25 and may be mounted in any suitable or desired manner, so as to be either movable or stationary in the window opening or the door opening.

What I claim as my invention is:

- 30 In a louver or shutter construction for doors and windows and other openings, the combination of a plurality of louver slats disposed in parallel relation to each other, a stationary pivot at each end of each louver 35 slat, and an up and down movable pivot at each end of said louver slat, stationary means engaging said stationary pivots, whereby these pivots are all in a fixed vertical plane, together with movable controlling 40 means engaging the movable pivot of each louver slat to control the motion of each slat about a stationary horizontal axis provided by its stationary pivots, said controlling means being movable downwardly and away 45 from the vertical plane of said stationary pivots, to open the slats, and stationary means to support said controlling means in the open position of the slats, said stationary and movable pivot engaging means comprising 50 a stationary cleat for engaging the stationary pivots, and a movable cleat for engaging the movable pivots, the two cleats having duplicate zigzag interengaging edges, whereby the two cleats in effect interlock 55 when the slats are in closed position, each cleat having its engaging edge of curved zigzag form, providing compound curves, and the engaging edge of one cleat being a duplicate of the engaging edge of the other 60 cleat, whereby the movable cleat moves toward and away from said stationary cleat.

Specification signed this 14th day of June 1930.

EARL PHILLIP JONES.
